FIG. 1.

FIG. 2.

INVENTOR
Morris Wuerpel
BY
Lyman E. Dodge
ATTORNEY

UNITED STATES PATENT OFFICE.

MORRIS WUERPEL, OF ROCHESTER, NEW YORK, ASSIGNOR TO GENERAL RAILWAY SIGNAL COMPANY, OF GATES, NEW YORK, A CORPORATION OF NEW YORK.

CIRCUIT-CONTROLLER.

1,170,033.

Specification of Letters Patent.

Patented Feb. 1, 1916.

Application filed May 18, 1915. Serial No. 29,007.

To all whom it may concern:

Be it known that I, MORRIS WUERPEL, a citizen of the United States, and a resident of the city of Rochester, in the county of 5 Monroe and State of New York, have invented a new and useful Circuit-Controller, of which the following is a specification.

This invention relates to controllers for electric circuits, and has for its main object 10 to provide a controller of this class which permits quick and easy readjustment of any one or more of its drum contacts relatively to opposed fixed contacts, and also allows ready and convenient substitution of one or 15 more worn or undesired drum contacts by others having like or differing circumferential adjustment, all without necessitating change of position of the remaining drum contacts relatively to their coacting fixed 20 contacts.

A further object of the invention is to provide a circuit controller having few, simple, inexpensive and durable parts including standard interchangeable drum sections, each adapted for application of a 25 peripheral contact and all having like general bodily form assuring interlocking engagement of any one section with an adjacent section or sections for causing rotation 30 of all the sections in unison from one driving part fixed to the drum shaft and engaging the first drum section.

Other objects and advantages will appear as the description of the invention progresses, and the novel features of the invention will be particularly pointed out in the appended claims.

Reference is made to the accompanying drawings forming part of this specification 40 and in which—

Figure 1 is a perspective view of the improved circuit controller, and Fig. 2 is a perspective view of one of the detached drum contact carrying sections.

The numeral 1, indicates any suitable base or support made of insulating material and to which in the example shown in Fig. 1, are fixed four coacting pairs of opposed 45 relatively fixed resilient finger contacts 2, and their binding posts 3, for line wire connections. In suitable bearings, 4, 4, shown fixed to opposite end parts of the base 1, is journaled the shaft 5, of a revolvable contact carrying drum 6, which besides its shaft 5,

comprises a series of any desired number of 55 rounded sections 7, of insulating material carrying conductive metal contacts 8, which fit upon the drum sections and may have any required length and are permanently fixed to said sections. These drum sections 60 7, each have a radial slot 9, opening to its periphery and made a trifle wider than the diameter of the drum shaft 5, and allowing all the drum sections to be laterally slipped upon the shaft prior to normal non-revolv- 65 able interlocking of them with each other by means of a series of alternating radial teeth 10, and recesses 11, of like size formed preferably at opposing faces of all the adjacent standard drum sections 7. All of said sec- 70 tions when normally interlocked at their toothed or serrated faces are securely held to each other and to the drum shaft 5, by opposite end clamping heads 12, 13. Both of these heads may have the general form of 75 head 12, which is shown with alternating facial teeth 10, and recesses 11, matching those of the drum sections 7, and having a reduced collar portion 14, through which and the shaft 5 passes a pin 15 securing the 80 head 12 non-revolvably to the shaft.

The clamping head 13, is shown as a plain washer which may be slipped over an externally threaded sleeve 16, fixed by a pin 17, to the drum shaft 5, and bears upon the 85 outside facial teeth 10 of the last drum section 7, to protect them against damaging pressure of the section fastening nut 18, screwed upon the sleeve 16, said nut being itself finally secured by an outer lock nut 90 19 movable on the sleeve. A crank arm 20, fixed to the drum shaft 5 provides for connection of a drum actuating rod leading from a movable part of any machine or device actuated by electric circuits governed 95 by the controller.

As the clamping head 12, is fixed by the pin 15, to the drum shaft 5, and as the first drum section 7, has teeth and recesses 10, 11, engaging like recesses and teeth of the head 100 12, said first section 7, must turn with the shaft 5 and head 12, and cannot turn independently of them, and as the following sec- 105 ond to last drum sections 7, all likewise engage each other by teeth and recesses 10, 11, it is obvious that through the clamp head 12 as a driver, all the drum sections 7, will turn together when the drum is turned by its

crank arm 20. In Fig. 1 of the drawings, the contact 8 of the last drum section 7, is shown engaged by the opposing pair of contact fingers 2, 2, to close a circuit at this section, while the circuits are open at the other three pairs of fingers. Should it be desired to change the circumferential adjustment of any one or more of the drum contacts 8, this may easily and quickly be done by turning back the nuts 18, 19, on the drum shaft sleeve 16, sufficiently far to allow disengagement of the teeth and recesses 10, 11, of the to be changed section 7, from the adjacent sections and said section then may be turned manually through a space equaling the distance between any two or more of the teeth 10, until the required circumferential adjustment of its contact 8, is effected and the separated drum sections then will again be engaged and the nuts 18, 19, will be again turned inward on the sleeve 16, to securely bind all the drum sections to each other for rotation in unison with the shaft 5, as the crank 20, is turned. It will be specially noticed that the above described circuit controller construction not only provides for this circumferential readjustment of any one or more of the drum sections 7, to change the position of their contacts 8, relatively to the stationary contact fingers 2, but it also assures that should any one or more of the drum section contacts 8, be damaged, or should it for any reason be desired to substitute other contacts 8, at like positions lengthwise of the drum, this also may be done by slipping the loosened and facially disengaged drum section or sections laterally off the drum shaft at the section slots 9, and slipping substitute sections at their slots 9, upon the shaft and again tightening the nuts 18, 19 to lock all the rearranged and facially engaged drum sections to each other and to the shaft. These circumferential or substitution adjustments of the drum sections may be made without rotating the unchanged or unremoved drum sections on the shaft and, therefore, without altering the desired relation of the unchanged section contacts to their opposed relatively stationary resilient finger contacts.

All of the drum sections 7, may not have the open radial slot 9, permitting their above described lateral bodily removal from or adjustment to the drum shaft without disturbing the circuit closing adjustment of the other sections, but it is preferred to form the radial slot in all of the drum sections which gives them the same general form permitting their use interchangeably relatively to each other at any position along the drum shaft.

The like formed standard drum sections 7, may be easily and cheaply produced in one operation by a molding process, which may

simultaneously fix or mold in the conductive contacts 8, thus leaving the drum sections ready for use without boring or facing or otherwise machining them.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. A circuit controller drum comprising a shaft, a plurality of contact carrying sections, means holding the drum sections to each other and means holding the sections to the shaft, said drum sections having an open slot permitting their lateral application to or withdrawal from the shaft when released from said holding means.

2. A circuit controller drum comprising a shaft, a plurality of mutually interlocking and circumferentially adjustable contact carrying sections applied around the shaft, a part fixed to the shaft and interlocking with the adjacent drum section whereby all the interlocking drum sections will turn in unison with the shaft, and means clamping the drum sections together endwise of the shaft; said drum sections having an open slot permitting their lateral application to or withdrawal from the shaft when unlocked from the adjacent drum sections or parts.

3. A circuit controller drum comprising a shaft, a plurality of mutually interlocking and circumferentially adjustable and interchangeable contact carrying sections applied around the shaft, a part fixed to the shaft and interlocking with the adjacent drum section whereby all the interlocking drum sections will turn in unison with the shaft, and means clamping the drum sections together endwise of the shaft; said drum sections having an open slot permitting their lateral application to or withdrawal from the shaft when unlocked from the adjacent drum sections or parts.

4. A circuit controller drum comprising a shaft, a plurality of mutually interlocking and circumferentially adjustable contact carrying sections applied around the shaft, a clamp-head fixed to the shaft and interlocking with the first drum section whereby all the interlocking drum sections will turn in unison with the shaft, which has a screw-threaded portion, a second clamp-head outside the last drum section, and a nut on the shaft screwthread outside said second clamp-head securing all the interlocking drum sections together endwise of the shaft; said drum sections having an open slot per-

mitting their lateral application to or withdrawal from the shaft when unlocked from the adjacent drum sections or parts.

5. A circuit controller drum comprising a shaft, a plurality of mutually interlocking and circumferentially adjustable and interchangeable contact carrying sections applied around the shaft, a clamp-head fixed to the shaft and having the same interlocking connection with the first drum section as the sections have with each other, and a second clamping means outside the last drum section securing all the interlocking drum sections together endwise of the shaft; 10 said drum sections having an open slot permitting their lateral application to or withdrawal from the shaft when unlocked from the adjacent drum sections or parts.

15 6. A circuit controller drum comprising a shaft, a plurality of mutually interlocking

and circumferentially adjustable and interchangeable contact carrying sections applied around the shaft, a clamp-head fixed to the shaft and having the same interlocking connection with the first drum section as the 25 sections have with each other whereby all the interlocking drum sections will turn in unison with the shaft which has a screw-threaded portion, a second clamp-head outside the last drum section, and a nut 30 on the shaft screwthread outside said second clamp-head securing all the interlocking drum sections together endwise of the shaft; said drum sections having an open slot permitting their lateral application to or withdrawal from the shaft when unlocked from the adjacent drum sections or parts. 35

MORRIS WUERPEL.
